W. C. TROUT

SAFETY EXPANSION BRAKE DRUM

Filed July 3, 1923

W. C. Trout

INVENTOR.

BY

Jesse R. Stone
his ATTORNEY.

UNITED STATES PATENT OFFICE.

WALTER C. TROUT, OF LUFKIN, TEXAS.

SAFETY EXPANSION BRAKE DRUM.

Application filed July 3, 1923. Serial No. 649,224.

To all whom it may concern:

Be it known that I, WALTER C. TROUT, a citizen of the United States, residing at Lufkin, Angelina County, Texas, have invented a certain new and useful Improvement in Safety Expansion Brake Drums, of which the following is a full, clear, and exact description, such as will enable others skilled in the art to which it appertains to make and use the same.

My invention relates to an improvement in brake drums and is particularly applicable to the type of brake drum used on draw works in connection with the operation of oil well drilling and pumping.

An object of my invention is to provide a detachable drum band for brake drums which may be easily manufactured and assembled, and which will be so constructed as to allow for expansion thereof under heat without damage to the same.

Another object is to provide a brake drum of the type described, having particular means for preventing the sliding of the said band relative to the drum.

These and other objects and advantages of my invention will appear more clearly from the more detailed specification which follows.

Referring to the drawing herewith, wherein a preferred embodiment of my invention is disclosed, Fig. 1 is a side elevation of a hoisting drum to which my improvement has been applied; certain parts being broken away for greater clearness; Fig. 2 is a central transverse section of one end of the hoisting drum taken approximately on the line 2-2 of Fig. 1; Fig. 3 is an assembled view showing the manner in which my brake is employed in connection with a hoisting drum.

In the use of a hoisting drum for drilling operations, it is a common difficulty to have the brake drum surface heat up excessively in use. This occurs principally when tools are lowered from the surface of the earth into deep wells. In such cases the weight on the cable causes the drum to rotate rapidly and it is necessary to apply the brake band to prevent too rapid dropping of the tools. In a deep well wherein the continuous unreeling of the cable lasts through an unusually long period, there is danger of the over-expansion of the brake drum and the lining thereof, and it is not uncommon to have the brake drum

expand unduly under heat, and break. With the employment of my invention it is believed that this common difficulty will be avoided.

In the drawing I have illustrated a brake drum 1 mounted upon a transverse shaft 2 for rotation with said shaft, the shaft in operation being mounted in bearings at each end thereof.

The drum comprises a central hollow cylindrical reel 3 having at each end a hub 4 fitting within the central opening therein. There is on said hub a radial flange or plate 5 forming a side supporting member for the hoisting drum. The reel 3 fits within an annular slot 6 in the side of said flange, thus making a close fit therewith. Spaced inwardly from the outer edge 7 of the flange 5 is a laterally extending drum support 8. The plate 5, as shown particularly in Fig. 1, is reinforced by strengthening ribs 9 extending like spokes of a wheel from the central hub outwardly to the said drum support. At spaced intervals along the drum support 8 on the inner surface thereof are formed bosses 10 through which transverse openings 11 are formed to allow the passage of connecting bolts 12. On the outer end of the drum support 8 is fitted a flat ring 13 which is adapted to engage with said drum support and has an inner face 14 thereon which, together with the plate 5 upon the hub forms a retaining device for a facing 15 for the drum. The said plate 13 is retained in position by said bolts 12 previously referred to.

In the adjacent faces of the plates 5 and 13 and spaced slightly outward from the brake drum support 8 are formed grooves or recesses 16 to receive the sides of the brake drum band 15. It will be noted that when the said band is placed in position and the plate 13 clamped in place by means of the bolts 12, the said brake drum band will be held securely in position. The facing 15 for the drum is made in a plurality of sections, and in the drawing I have shown four such sections. Each section 17 thus formed has an inwardly projecting lug 18 thereon which fits within a transverse groove 19 in the outer periphery of the drum support 8. There are four of such grooves,—one to accommodate the lug 18 on each of the four sections of the drum. The said sections are spaced slightly apart

at their adjacent ends to allow sufficient room for expansion under heat, and it will be noted that the lugs 18 fit somewhat loosely in the grooves 19 which receive them so as to accommodate a certain amount of expansion in all directions.

In the operation of my improved device, the hoisting drum is assembled in the manner shown and described, and the sectional brake drum band is secured in position upon the support 8. The outer plate 13 is then clamped in position by means of bolts 12. In this manner the drum is ready for use, and in case of wear or for other reasons it becomes necessary to renew or replace the removable drum, it may be done in an obvious manner without the necessity of an entirely new brake drum. When the device is being used the contact of the brake band 20 with the facing 15 for the drum will set up a certain amount of heat, and under continuous use this heat may become excessive. The fact that the sections of the drum are spaced apart and the drum itself mounted loosely in position, the expansion of the drum under this use may take place without injuring in any way the operation of the complete device. Accidents which ordinarily occur with the common type of brake drum will be thereby entirely eliminated.

While I have shown the application of my invention to draw works for well operations, it is obvious that it has a wide use and I do not wish to be confined to its application to this particular form of apparatus.

What I claim is new and desire to protect by Letters Patent is:

1. In a hoisting drum, a brake drum comprising a drum support, a removable

drum band made up of a plurality of sections spaced apart, means on each section to prevent slipping of said sections on said drum support, and means to secure said sections on said support, including an outer retaining plate on said support, having a groove to receive said sections.

2. In a hoisting drum, a brake drum, comprising a drum support, a removable drum band made up of a plurality of sections spaced slightly apart, a lug on each said sections fitting within a groove in the drum support and lateral retaining flanges, and means to secure said sections on said support.

3. In a hoisting drum, a brake drum, comprising a drum support, a removable drum band made up of a plurality of sections, and inwardly projecting lugs on said sections fitting loosely in grooves in said support whereby said drum band may expand under heat, and lateral flanges on said support to retain said drum band in position.

4. A brake drum comprising a hub, a radial flange thereon, a laterally projecting cylindrical drum support thereon, a removable drum band on said support made up of sections and means to secure said drum band on said support.

5. A brake drum comprising a hub, a radial flange thereon, a laterally projecting cylindrical drum support thereon, a removable drum band on said support made up of sections, means to secure said drum band on said support and means to prevent sliding of said drum band on said support.

In testimony whereof, I hereunto affix my signature this 31 day of May, A. D. 1923.

WALTER C. TROUT.
